PROCESS FOR THE PRODUCTION OF WOOL
FELT CAPELINES, AND THE PRODUCT
THEREOF

Joseph Gordon Jones and John Rowland Jones,
Surry Hills, near Sydney, New South Wales,
Australia, assignors to Jones Brothers Pty.
Limited, Sydney, Australia, a company of New
South Wales

Application February 8, 1937, Serial No. 124,754
In Australia October 12, 1936

2 Claims. (Cl. 28—1)

This invention relates to the production of
felted capelines or bodies from which felt hats
are made.

The production of capelines from wool by the
conventional methods is a relatively expensive
and slow process. Although different manufac-
turers use various processes for the production
of a wool capeline, and no process can be defi-
nitely specified as "the conventional method", it
is generally the fact that the wool is subjected
to a relatively large number of operations before
the finished capeline is produced, and the follow-
ing are operations generally employed:

15 Carding of the wool,
Forming of the body,
Hardening,
Bumping,
Planking, and
Tipping and brimming.

20 The capeline produced at this stage is regarded
as the "finished" capeline for the purposes of
this specification, although it may be dyed and/or
pounded before use. Furthermore, in wool felts
25 it is quite a common practice to re-bump and/or
re-plank the capeline after dyeing.

Machinery is now generally used in the indus-
try for each of the operations on the wool body,
and such machinery is complex and very expen-
sive. Moreover, the felt bodies have to be sub-
30 jected so many times to numerous operations
that the time taken to produce a capeline may
be twenty-four hours.

The object of the present invention is to pro-
35 vide a process which will produce a felted cape-
line from woollen yarn which has the appear-
ance of a wool felt capeline, but which is very much
simpler, quicker and less expensive to produce.
Whilst no claim is made that the capeline pro-
40 duced by our process is in all respects the equal
of a wool felt capeline, it has the obvious advan-
tage of cheapness and speed of production. The
number of operations necessary to produce the
"finished" capeline is materially reduced, the time
45 of production is reduced from approximately 24
hours to approximately 4 hours, and finally the
number of machines, and the complexity and
cost of the machinery necessary, is markedly re-
duced.

50 A further object of the invention is to produce
a capeline from woollen yarn by our process,
which is an excellent substitute for the wool felt
capeline, and which is produced at lower cost.
The capeline produced by our process has the
55 important merit that it is far more readily and

quickly blocked than the conventional wool cape-
line, as it is formed ab initio with a flared brim.

With the above objects in view the invention
consists of a process, and the product of that
process, as hereinafter claimed.

In order to fully describe the invention, ref-
erence is made to the accompanying drawing, in
which:

Fig. 1 is a perspective view showing a unit from
the knitting machine, severed from the gang, 10

Fig. 2 is a perspective view showing the unit of
Fig. 1 stitched to form a hood,

Fig. 3 is a perspective view of the hood after
fulling, and

Fig. 4 is a perspective view of the capeline after 15
fulling.

The drawing shows the capeline in the four
main stages of its production. No detailed ref-
erence is made in this specification to the ma-
chinery by which the processes are carried out, 20
since any skilled technician will have no diffi-
culty in using standard machinery for this pur-
pose.

In the first stage woollen yarn is machine
knitted, as on a machine suitable for knitting 25
berets, into a gang of conjoined units each hav-
ing a curved shape and conjoined by short
straight knitted portions 3.

One of the units, severed along the straight
portions from the gang, is shown in Fig. 1. It 30
will be seen that the yarn is knitted into a curved
body 1 having a partially-circular crown portion
2 which, with the sides of the body, extend into
the straight portions 3, 3 which originally con-
joined the unit to the gang. The knitting ma-
chine is adjusted, or adapted (in a manner which
will be known to, or readily accomplished by, a
skilled technician) to form the lower part of
the body with a flared brim portion 4, the ad-
vantage of which will be hereinafter detailed. 40

The number of stitches used in knitting the
body increases (substantially uniformly) from
the crown portion 2 to the commencement of the
brim portion 4, and in the brim portion the num-
ber of stitches increases at a greater rate, to 45
permit the brim to take a flared relationship to
the body. This method of knitting permits the
subsequent formation of the body into a conical
hood, with a brim flaring therefrom, without any
unnatural stretching of the hood. Moreover, this 50
shape is obtained with a uniform density of the
material throughout the hood, resulting in a uni-
formly dense capeline after fulling.

The body unit 1 is severed by hand cutting
from the gang and has its open sides conjoined 55

in a linking machine which trims the ragged edges of the hand cut just before it links the open sides. In this machine the open sides are neatly and flatly conjoined, and the straight portions 3, 3 cut therefrom, to form the approximately conical hood 5 shown in Fig. 2. It will, however, be noted that the hood retains the flared brim 4, which is in fact retained throughout the manufacture of the capeline. At this stage the hood 5 is, of course, soft and limp, as with any knitted article.

The hood 5 is then subjected to partial scouring in a bath of soap and soda ash, to remove a proportion of the grease in the yarn. The extent of this preliminary scouring is not particularly material, and in fact it may possibly be omitted, as very complete scouring is effected in the stage next following. However, the preliminary scouring is convenient in preventing excessive contamination of the fluid in the next stage.

The hood is then subjected to the fulling operation in a fulling machine, as used for beret manufacture. The fluid in the fulling machine is again soap and soda ash, which completes (or effects) the scouring during the fulling operation. After the scouring is completed but before the fulling is finished, the soap and soda ash (with the now emulsified grease) is washed out and the fulling is continued using a dilute solution of sulphuric acid. It is to be noted that at no time during the fulling process, is it necessary to stop the machine. The hood is preferably subjected to fulling for about two hours, and in the process is considerably reduced in size, whilst the yarn is very well felted or compacted. Fig. 3 illustrates the hood after fulling, when it is termed a capeline (6), and it will be observed that the flared brim 4 is very evident.

The felted capeline 6 is then treated in a hardening machine, until the required felted texture is attained. This hardening treatment further compacts the capeline. Figure 4 shows the capeline 7 after hardening, when it is regarded as a "finished" capeline for the purposes of this specification, and is the equivalent of the wool felt capeline after the tipping and brimming operation mentioned above.

Obviously, further operations such as dyeing and pouncing may be carried out on the capeline, but as these are similar to the operations carried out on the wool felt, no importance is attached thereto.

It will be realized by any expert hat manufacturer that the flared brim portion 4 formed on the felted capeline 7 completely eliminates the necessity of tipping and brimming, and moreover facilitates the blocking of the capeline.

It will also be very clear that the machinery necessary to manufacture the "finished" capeline according to the above process is very considerably less, and is much simpler and less expensive, than the modern machinery necessary to manufacture a "finished" capeline from wool by usual methods. Not only is a great saving effected in plant, but the time of production is only a fraction of that required for a wool felt, and hence labour costs are much reduced, and production accelerated.

The invention does not depend upon the composition of the yarn used, and it is intended that the expressions "wool" and "woollen yarn" in the specification and claims shall include yarns made from fur, which can be suitably knitted.

We claim:

1. A capeline comprising a body of knit material having a flared-knit brim and a conical portion, said body, in course of manufacture, having a longitudinal opening from whose edges extend straight-knit portions, and means securing said edges together thereby closing said opening, said body being completely fulled.

2. The process of manufacturing capeline from woollen yarns, comprising the knitting of the yarns into a body of generally conical form with a flared brim and with an opening extending from brim to peak leaving straight knit portions extending from each edge of the body along said opening, closing the opening and sewing the edges together, and thereafter scouring and fulling the body into a capeline.
